UNITED STATES PATENT OFFICE.

WALTER DYER, OF PORTLAND, OREGON.

PROCESS FOR MAKING DRYING-OILS FROM MINERAL OILS.

1.256.535.

Specification of Letters Patent. Patented Feb. 19, 1918.

No Drawing.

Application filed November 7, 1916. Serial No. 130,038.

To all whom it may concern:

Be it known that I, WALTER DYER, a subject of the King of England, residing at Portland, in the county of Multnomah and State of Oregon, have invented certain new and useful Improvements in the Process of the Manufacture of the Mineral Oil, and I do hereby declare the same to be fully known, and described, except so much of the invention as is set forth in the following specification, which is appurtenant to the said invention, and which is set forth in the annexed drawing, which drawing is a sketch of the apparatus used in the preparation of the oil.

151. *Exercitio de rebus publicis. De rebus publicis. De rebus publicis. De rebus publicis.*

32. The following table gives the experimental results obtained in the series of experiments made by the mineralogist in the laboratory of the Bureau of Standards, from which it is evident that the *Wadsworth test* is not a good test for the detection of the presence of gold in gold-bearing minerals.

very badly, leaving the concrete exposed. Paint containing oil made in accordance with the present description is found to be much more permanent, when applied to 5 concrete or cement work than linseed oil.

What I claim is:

1. A process which comprises boiling a mixture comprising non-drying mineral oil and alcohol for a sufficient length of time to 10 convert the mineral oil into a drying oil.

2. A process which comprises boiling a mixture comprising a relatively large bulk of a heavy non-drying mineral oil from which the gasoline and kerosene fractions 15 have been removed, and a relatively small

bulk of alcohol for a sufficient length of time to convert the mineral oil into a drying oil.

3. A process which comprises boiling a mixture comprising about 10 to 20 parts of mineral oil to one part of alcohol for a sufficient length of time to convert the mineral oil into a drying oil. 20

In testimony whereof I have hereunto set my hand in the presence of two subscribing witnesses.

WALTER DYER.

Witnesses:

EVERETT A. JOHNSON,
ALBERT B. RIDGWAY.
